UNITED STATES PATENT OFFICE.

HENRY I. CARVER, OF LUDLOW, MASSACHUSETTS.

BUTTER MOLD AND STAMP.

SPECIFICATION forming part of Letters Patent No. 351,042, dated October 19, 1886.

Application filed July 19, 1886. Serial No. 208,384. (No model.)

To all whom it may concern:

Be it known that I, HENRY I. CARVER, a citizen of the United States, residing at Ludlow, in the county of Hampden and State of Massachusetts, have invented new and useful Improvements in Butter Molds and Stamps, of which the following is a specification.

This invention relates to improvements in butter molds and stamps in which the stamp proper is adapted to form one side of the mold or stamp-box, into which the butter is forced to give it form, said stamp being movable and adjustable to different positions; and the invention consists in the peculiar construction and arrangement of various parts of the device, all as hereinafter fully described, and set forth in the claims.

In the drawings, forming part of this specification, Figure 1 is a perspective view, and Fig. 2 is a longitudinal section, of a butter-stamp embodying my improvements. Figs. 3 and 4, are respectively top and bottom plan views of the metallic stamp-box frame or yoke.

In the drawings, 2 is a metallic yoke or frame, made of cast-brass or other suitable metal, Fig. 3 showing the top of said frame, and Fig. 4 the under side thereof before any of the stamp parts are attached thereto. Cross-braces 3 are applied to the under side of the central part of the frame (see Figs. 2 and 4) to make the latter rigid. A slot, 4, is made therethrough, through which the stamp-handle 7 passes, and two holes, 5, are provided therein, in which two adjusting-screws, 6, are fitted.

The frame 2 is open at the point thereon indicated by 8, in order to keep it as light as practicable, and it is provided with a series of transverse openings, 9 and 10, to receive one end of each of the sides 12 and 13 and the ends 14 and 15 of the stamp-box 16, arranged in the manner shown in Fig. 1—that is to say, the upper edge of the side 13 within the frame 2 extends from the inner side of the end 15 at *a* to the point *b*, or to the end of one of said openings 9 against the inner side of the frame. The upper edge of the side 12 in the opposite side of the frame is similarly arranged, and extends from the inner side of the end 14 of the box at *c* to the opposite end of the frame at *d*. The end 15 within the frame extends

between the side 12 and the inner opposite side of the frame, and the end 14 within the frame extends between the side 13 and the inner opposite side of the said frame.

The sides and ends of the stamp-box are cut, as shown in Fig. 2, to let the frame 2 partly into their outer sides, so that the latter and the outside of the frame shall be flush or in the same plane, and their upper ends are slotted longitudinally to allow the cross-tie parts 26 of the frame to enter them as they are driven into the latter, said sides and ends of the stamp-box being made of hard wood (maple, preferably) and driven very tightly into said metallic frame, thereby being made to assume the relative positions shown. In practice it is not found necessary to secure said sides and ends of the box to the metallic frame by pins or screws passing transversely through the latter, but they may be so inserted, if thought desirable. The frame 2 has a recess, 17', formed in each end, in which the fingers are inserted to lift the box when it is not manipulated by the stamp-handle 7.

The object in making the stamp-box by providing the aforesaid metallic frame and attaching the sides and ends of the box thereto, as described, is to avoid the separation and displacement of said side and end parts by shrinking and swelling, which is common to butter-stamp boxes when said parts are secured around a wooden center block in the usual way. The inconvenience resulting from said separation and displacement of the box parts is understood when it is explained that with a proper adjustment of the stamp from the open end of the box, as below set forth, by the use of said box balls or blocks of butter can be molded which are of almost exact uniformity of weight, and any displacement of the box parts causes a variation in said weight.

The stamp 17 is made, preferably, of hard wood, having any fanciful or other figure or figures on its face, and is made to be moved up and down within the stamp-box by means of the handle 7. A metallic plate, 18, having an upstanding screw-threaded socket, 19, thereon, is secured to the upper side of the stamp, as shown.

The stamp-handle 7 has a shank, as shown, the end of which is screw-threaded to enter

said socket 19, and is provided with laterally-projecting stops 20, to hold the handle and the stamp up, as shown in Figs. 1 and 2. A spiral spring, 21, having one end attached to the 5 under side of the frame 2, surrounds the lower end of the said shank and bears against the upper side of the stamp-plate 18, serving thereby to assist in starting the stamp downward after the box has been filled with butter.

10 Two screws, 6, in the top of frame 2, are adjustable longitudinally toward and from the stamp 17, to bring the latter to such a position in the box as shall cause a block of butter of a certain weight or thickness to be molded, and

15 to accommodate such variation of the position of the stamp the handle of the latter is screwed more or less into or out of the socket 19, so that whatever the position of the stamp the handle may be operated to engage the stops 20 with the top of frame 2 in the manner shown, the screws 6 and said handle being co-operatively adjusted for said purpose.

When the stamp-box is filled with butter by forcing it thereagainst in the usual way, the 25 handle 7 is turned to bring the stops 20 in a line with the slot 4 in frame 2, and by bearing against the T-shaped part of said handle the stamp is forced against the butter, driving it out of the box. The stamp is then drawn 30 backward by the handle, and the latter is then turned to the position shown in Figs. 1 and 2, and the operation is repeated.

The metallic parts of the butter-stamping device—that is to say, the handle 7, the frame 2, the plate 18, the screws 6, and spring 21— 35 may all, or any part thereof, be nickel or

silver plated, thereby avoiding any corrosion, and aiding in keeping them clean more easily. If desired, the side and end pieces of the stamp-box may be made of paper or of 40 hard rubber or other similar plastic material instead of wood.

What I claim as my invention is—

1. A box for a butter-stamp, consisting of a metallic frame, 2, having transverse openings 45 therethrough, and of side and end pieces of wood or of analogous material, said pieces having one end thereof entering said transverse openings in the frame, and secured thereto, substantially as set forth. 50

2. A butter-stamp consisting of a metallic frame, 2, having sides and ends of wood or analogous material secured thereto, forming an open-ended box, a stamp adapted to be moved within the latter, having a screw-threaded socket thereon, a stamp-handle passing through said frame, and having a screw-threaded end entering said socket, and two screws passing through said frame and adjustable in the direction of their length toward 60 and from said stamp, substantially as set forth.

3. In combination, the stamp-box having the slot 4 in the frame thereof and the two adjustable screws 6 in the latter, the stamp 17, having the screw-threaded socket 19 thereon, the 65 stamp-handle 7, screwed to fit the latter, and having the lateral stops 20 thereon, and the spring 21, substantially as set forth.

HENRY I. CARVER.
